HANDWHEEL FOR LOOMS

Alexander C. Krukonis, Worcester, Mass., assignor to Crompton & Knowles Loom Works, Worcester, Mass., a corporation of Massachusetts

Application October 29, 1945, Serial No. 625,321

8 Claims. (Cl. 139—1)

1

This invention relates to improvements in the hand wheels of looms and it is the general object of the invention to provide a hand wheel normally disconnected from the loom during loom operation but connected to the loom when the latter is stopped to permit manual operation of the loom.

It has been customary in the past to provide looms with hand wheels keyed or otherwise secured to the top shaft of the loom to permit the loom to be turned over by hand. Such a hand wheel when turning with the shaft during loom operation has a momentum which must be arrested when the loom protects. It is an important object of my present invention to construct and control the hand wheel in such manner that it will ordinarily be at rest so that when the loom protects there will be no hand wheel momentum energy to be dissipated.

A loom will ordinarily protect during forward movement of the lay with part at least of the shuttle in the warp shed and the shuttle can be removed from the shed only by turning the loom in a reverse direction to move the lay rearwardly far enough to permit the shuttle to be taken out of the shed. This reverse movement cannot ordinarily be derived from the loom driving mechanism and shipper handle of the loom, since the driving mechanism will drive the loom in a forward direction only. It is another object of my present invention to provide a stationary hand wheel which will be connected to the loom at the time of protection so that the lay can be given a reverse motion sufficient to permit removal of the shuttle from the shed.

In order that there may be no tendency on the part of the turning shaft of the loom to cause rotation of the hand wheel it is still another object of my invention to mount the hand wheel independently of the shaft. This may be accomplished by supporting the hand wheel or some part of it in a stationary bearing in such manner that all parts of the hand wheel will be out of contact with the shaft during loom operation.

It is another object of my invention to provide means by which the shipper mechanism when moving from running to stopping position will automatically connect a normally idle hand wheel to one of the loom shafts so that the loom can be turned over by hand whenever the shipper mechanism is in stopping position.

At the time the loom protects considerable energy must be dissipated in a very short interval of time and it is another object of my invention

2

to connect the stationary hand wheel to the loom, as for instance to the aforesaid shaft, during the protecting interval so that a part of the energy to be dissipated can be spent in overcoming the inertia of the hand wheel. Because of this latter feature of my invention it will be seen that the stationary hand wheel not only reduces the total amount of energy which must be dissipated at the time of protection, but also absorbs part of this energy.

With these and other objects in view which will appear as the description proceeds, my invention resides in the combination and arrangement of parts hereinafter described and set forth.

15 In the accompanying drawings, wherein a convenient embodiment of my invention is set forth,

Fig. 1 is a plan view of the driving end of a loom having my invention applied thereto,

Fig. 2 is an enlarged vertical section on line 20 2—2 of Fig. 1,

Figs. 3 and 4 and 5 are vertical sections on lines 3—3, 4—4 and 5—5, respectively, of Fig. 2,

Figs. 6 and 7 are diagrammatic views showing the hand wheel and the shipper handle controlling it in two different positions,

Figs. 8 and 9 are diagrammatic views showing the position of the protector mechanism and the shuttle in two different positions, and

Fig. 10 is a side elevation looking in the direction of arrow 10, Fig. 1, showing the shipper and brake handle in position for turning the loom over by hand after the loom has been stopped by the protector mechanism.

Referring particularly to Figs. 1 and 10, I have shown a loom frame 10 having a breast beam 11 and an outboard bearing frame 12 fixed with respect to the loom frame. Inner and outer bearings 13 and 14, respectively, are provided for the top or crank shaft 15 of the loom. The latter shaft is driven by mechanism part of which is shown in Fig. 1 and including a driving gear 16, clutch 17, shipper lever 18 for the clutch, and a brake band 19 extending around the brake drum 20 secured to the shaft 15. The shipper lever 18 is pivoted as at 21 with respect to the outboard bearing frame 12 and is attached to a link 22 connected to a bell crank lever 23 pivoted on a stand 24 fixed with respect to the loom frame.

40 A rod 25 extends forwardly from the bell crank lever and is connected to a rocking lever 26 pivoted on a fixed stud 27. A link 28 connects the rocking lever with the shipper handle 29 which is secured to the shipper shaft 30. When the shipper handle is in the rear or stopping position shown in Fig. 7 the shipper lever 18 will

be moved outwardly or away from the loom frame to move the clutch 17 to non-operating position with the shaft 15 disconnected from the driving gear 16.

A brake handle 35 is pivoted on the shipper shaft 30 and is connected to a link 36 pivoted to a second rocking lever 37 moving about fixed stud 21. An actuating screw 38 on the link 36 is positioned for engagement with the lower part of the shipper handle. A brake rod 39 extends rearwardly from lever 37 and is pivoted to the lower end of a brake band lever 40 the other end of which is attached to a spring 41. That end of the spring 41 remote from lever 40 is anchored with respect to the loom frame and the spring normally tends to rock lever 40 in a counter-clockwise direction as viewed in Fig. 10, or in the direction to move the brake band 19 against the brake drum 20.

During normal running conditions both the shipper handle and the brake handle will be in forward position, or to the left as viewed in Figs. 1 and 10, spring 41 being overpowered by the locking relation of link 36 and lever 37 so that band 19 will be spaced slightly from the drum 20. Under these conditions also the shipper lever 18 will be held in the driving position shown in Fig. 1 and gear 16 will be connected to shaft 15 through the clutch 17.

The loom protector mechanism includes a protector rod 45 carried by the loom lay L and having a dagger 46 the position of which is determined by the shuttle S. If as the lay advances the shuttle is properly boxed the protector dagger 46 will be in down or non-stopping position and as the lay is moved forwardly by shaft 15 the dagger will pass below a bunter or stop lever 47 pivoted with respect to the breast beam at 48. If the shuttle should not be properly boxed, however, and should remain trapped in the warp shed, see Fig. 8, the dagger will remain in raised position and as the lay advances it will cause dagger 46 to engage lever 47 and rock the latter, causing its outer end 49 to engage an upstanding horn 50 on the brake handle. Under these conditions the brake handle 35 will be rocked in a clockwise direction as viewed in Fig. 10 and the actuator screw 38 will be moved against the shipper handle to rock the latter from the running to the stopping position shown in Fig. 10. The result of this operation will be to stop the loom and leave the brake band tight against the drum 20.

In order to permit manual operation of the loom the brake handle 35 will then be moved forwardly to the off or running position to slacken the band 19 with respect to the drum 20. This forward movement of the brake handle is made possible by the fact that the lay ordinarily rebounds somewhat as the result of protection, and the end 49 of the bunter lever 47 merely initiates application of the brake to unlock the brake link 36 with respect to the lever 37 to permit spring 41 to apply the brake. There is therefore a certain amount of lost motion between the horn 50 and the end 49 of lever 47 which will permit forward movement of the brake handle after the loom has been stopped by engagement of the dagger 46 with the lever 47.

The matter thus far described is of common construction and of itself forms no part of my present invention and may be made as set forth in prior patent to Brouwer No. 2,055,228. It is thought sufficient for present purposes to state that when both the brake and shipper handles are in forward position, or to the left as viewed

in Fig. 10, the loom will be in operation. When the loom protects, however, the brake handle will be rocked rearwardly to permit application of the brake and the shipper handle will move rearwardly from running to stopping position. The brake handle can then again be moved forwardly to its running or off position while the shipper handle remains in stopping position.

In carrying my present invention into effect I provide means by which a hand wheel normally stationary during loom operation can be connected automatically to the shaft 15 when the loom is stopped, as by the protector mechanism. The hand wheel 60 shown more particularly in Fig. 2 has a sleeve 61 secured thereto as at 62. This sleeve fits into and is supported by a stationary bearing 63 secured to the outboard bearing frame 12 by means of bolts 64. These bolts also hold a disk 65 against the outboard frame 12. The sleeve is rotatable relatively to bearing 63 and can also slide in the latter axially of shaft 15.

A sleeve 66 surrounding shaft 15 has a clutch head 67 secured to the shaft by means of a pin 68. The sleeve 66 forms part of the previously mentioned bearing 14 and engages rollers 69 two of which are shown in Fig. 2. These rollers turn in the bearing 14 and constitute a roller bearing supported by the outboard bearing frame 12 and affords means for supporting the outer end of the shaft 15. A clutch disk 70 is secured as at 71 to the sleeve 61 and has teeth 72 to engage teeth 73 of the head 67.

In order to control the position of the hand wheel and sleeve 61 I provide a lever 75 pivoted as at 76 on a small stand 77 secured to the outboard frame 12. A link 78 connects lever 75 to the shipper lever 18 and causes these two levers to move together. Lever 18 may be provided with a stud 79 shown in detail in Fig. 2 to operate the clutch mechanism 17.

The lever 75 is provided with pins 80 which fit into a groove 81 formed in the periphery of sleeve 61. When lever 75 is rocked the pins 80 cause longitudinal movement of the hand wheel and sleeve 61 with respect to the shaft 15 and also cause relative movement of the clutch members 67 and 70.

Under normal running conditions the link 78 will be caused by shipper lever 18 to hold the clutch members separated as shown in Fig. 2. At the time of protection, however, the shipper handle will be rocked from the position of Fig. 6 to that of Fig. 7 by the actuating screw 38 as already described, thereby unlocking lever 26 and permitting spring 74 to act through rod 25 to cause angular movement of the shipper lever 18 to operate clutch 17 in such manner as to disconnect shaft 15 from the driving gear 16. This movement of the shipper lever rocks lever 75 and causes the pins 80 to move the sleeve 61 into the bearing 63, thereby causing engagement of clutch member 70 with the clutch member 67. This engagement of the clutch member automatically connects the hand wheel to the shaft 15 and it is then possible to reverse the direction of the loom to move the lay L rearwardly far enough to permit the shuttle trapped in the warp shed to be removed.

Fig. 8 shows diagrammatically the relation of the shuttle S with respect to the warp shed W at the beginning of the protector operation, and Fig. 9 shows the relation of the parts upon completion of the protector operation after the lay has moved forwardly slightly from the position of Fig. 8. It will be obvious from Fig. 9 that it is necessary to turn the loom backwardly in order

to get the shuttle out of the warp shed and this reverse movement can be accomplished as already stated by means of the hand wheel.

As shown more particularly in Fig. 2 all parts which move with the hand wheel are out of engagement with the shaft 15 when the loom is running. The bore 85 of the clutch disk 70 is of somewhat larger diameter than the shaft 15 and the latter passes through a hole 86 in the hand wheel which is also larger than the shaft. The bearing 63 is preferably concentric with shaft 15 so that it maintains the hand wheel and all parts of the latter out of engagement with the shaft for all longitudinal positions of the hand wheel and also for all angular positions of the shaft.

As already indicated an important feature of my invention resides in the fact that the hand wheel can be clutched to the shaft 15 while the latter is still turning during the protecting interval, and for this reason part of the energy which must be dissipated at the time of protection can be absorbed by overcoming the inertia of the hand wheel. Ordinarily the actuator screw 38 of the brake lever will be set very close to the shipper handle so that for all practical purposes the shipper handle moves as soon as the brake handle is moved by the protector mechanism. After the protector dagger engages the lever 47 the latter moves an appreciable fraction of a second during the protector interval before the lay actually comes to rest. During the first part of this interval the shipper handle will have moved far enough to establish initial engagement between the clutch member 67 and 70, at which time the shaft 15 is still turning. At the time of this initial engagement the hand wheel starts to turn and the amount of energy which must be expended in getting the hand wheel into rotation is derived from the energy of the shaft 15 which must be dissipated during the protecting operation. It will therefore be seen that by having the hand wheel ordinarily stationary and connected to the shaft during the protecting operation, two beneficial results are effected the first of which is that the total energy to be dissipated is reduced due to the fact that the hand wheel is stationary, and a part of this reduced energy is utilized in getting the hand wheel into motion.

From the foregoing it will be seen that I have provided simple means by which a hand wheel normally stationary during loom operation is automatically connected to the driving shaft upon loom stoppage due to operation of the protector mechanism to permit manual reversal of the lay so that the shuttle trapped in the warp shed can be removed. It will also be seen that the hand wheel is radially spaced from shaft 15 and is so mounted that during loom operation it is out of engagement with the shaft and can remain stationary so that it has no momentum energy to be dissipated at the time of protection. Furthermore, movement of the shipper mechanism from running to stopping position effects engagement of the clutch member 67 and 70 to connect the hand wheel operatively to the shaft 15. While this connection of the hand wheel to the shaft occurs upon all stoppages of the loom, it is particularly useful when the loom is stopped by the protector mechanism, since under these conditions the loom cannot be operated by power and must be reversed manually. It will further be noted that by connecting the hand wheel to the shaft 15 during the protecting interval and while

the shaft 15 is still in motion a part of the energy which must be dissipated incident to protection is absorbed by overcoming the inertia of the hand wheel.

- 5 Having thus described my invention it will be seen that changes and modifications may be made therein by those skilled in the art without departing from the spirit and scope of the invention and I do not wish to be limited to the details herein disclosed, but what I claim is:
1. In a loom having a shaft which turns during loom operation to reciprocate a lay and in which the shaft and lay are at rest when the loom is not operating, shipper mechanism controlling 15 operation of the loom and movable to running and stopping positions, loom protector mechanism to move the shipper mechanism from running to stopping position by a force derived from the lay upon improper presence of a shuttle in the warp shed, a stationary bearing surrounding the shaft, a hand wheel rotatable on and slidably longitudinally along said bearing axially of the shaft, and connections between said shipper mechanism and said hand wheel effective when the shipper mechanism is moved to stopping position by the protector mechanism to move the hand wheel bodily axially of the shaft and connect the hand wheel operatively to the shaft.
2. In a loom having a lay, a shaft by which the lay is reciprocated backwardly and forwardly due to rotation of a shaft during loom operation, a stationary bearing concentric with the shaft, a hand wheel supported by and mounted for rotation with respect to the bearing, said hand wheel being radially spaced from and out of engagement with the shaft and remaining at rest during loom operation, a clutch member secured to and rotating with the shaft, a clutch member fixed with respect to the hand wheel, loom shipper mechanism, and means controlled by the shipper mechanism to cause engagement of said clutch members to connect the hand wheel operatively to the shaft when the shipper mechanism is in non-running position.
3. In a loom having a lay reciprocated by a shaft which rotates during loom operation, a clutch member secured to and rotating with said shaft, a hand wheel concentric with the shaft and movable axially and independently of the shaft, a second clutch member rotatable with the hand wheel and normally out of engagement with the first clutch member during loom operation to enable said hand wheel to remain stationary, and means operative upon loom stoppage to effect axial movement of the hand wheel and second clutch member along the axis of the shaft to effect engagement of said clutch members to connect the hand wheel operatively to said shaft.
4. In a loom having a lay reciprocated backwardly and forwardly due to rotation of a shaft during loom operation, a fixed bearing concentric with the shaft, a hand wheel having a hub rotatably mounted in and slidably axially with respect to the fixed bearing, a clutch member fixed with respect to the shaft, a second clutch member fixed with respect to the hub, shipper mechanism movable from running position when the loom is operating to stopping position when the loom stops, and connections between the shipper mechanism and said hub operated by a force derived from the lay to move the hand wheel axially of the shaft and then cause engagement of said clutch members to connect the

hand wheel operatively to the shaft when the shipper mechanism moves to stopping position.

5. In a loom having a lay reciprocated by a shaft which rotates during loom operation, a clutch member rotating with said shaft, a hand wheel, a fixed bearing extending around the axis of said shaft, said hand wheel rotatable on said bearing and capable of sliding movement on said bearing axially of the shaft, a second clutch member fixed with respect to the hand wheel and out of engagement with the first clutch member during loom operation, and means operated by a force derived from the lay incident to loom stoppage to move said hand wheel axially of the shaft to effect engagement of said clutch members to connect the hand wheel operatively to the shaft while the lay is moving.

6. In a loom having a frame provided with an outboard support provided with a bearing in which a lay operating shaft rotates during loom operation, a shipper lever pivoted with respect to the outboard support and when in running position causing rotation of the shaft and operation of the loom, the loom and shaft being stationary when the shipper lever is in stopping position, a fixed bearing concentric with the shaft and mounted by said outboard support, a hand wheel having a hub rotatable in and slideable longitudinally of said fixed bearing and axially of the shaft, clutch members one of which rotates with the shaft and the other of which rotates with the hand wheel, and means connected to said shipper lever and effective when the latter moves from running to stopping position to move said hand wheel axially of the shaft in said stationary bearing to cause engagement of said clutch members and thereby operatively connect the hand wheel to the shaft.

7. In a loom having a lay, a lay operating shaft which rotates during loom operation and is at rest when the loom is not operating, shipper mechanism in running position when the shaft is rotating and in stopping position when the shaft is at rest, a clutch member secured to and rotating with the shaft, a hand wheel for the shaft stationary during loom operation, means

mounting the hand wheel concentrically with but independently of the shaft when the latter is rotating, a second clutch member concentric with said shaft and first named clutch member secured to and rotatable with the hand wheel, and means controlled by the shipper mechanism to effect relative movement of said clutch members to effect engagement thereof when the shipper mechanism moves to stopping position to connect the hand wheel operatively to the shaft.

8. In a loom having a lay and an operating shaft therefor which rotates during loom operation and comes to rest when the loom stops, shipper mechanism in running position when the shaft is rotating, means transmitting a force from the lay to the shipper mechanism to cause the latter to move to stopping position to bring the shaft and lay to rest, a hand wheel for the shaft mounted for axial and rotary motion relatively to and independently of the shaft and normally at rest and operatively disconnected from the shaft during loom operation, and means actuated by a force derived from the lay and transmitted through the shipper mechanism when the latter is moved to stopping position by action of the lay first to move the hand wheel along the shaft and then connect the hand wheel operatively to said shaft, whereby the inertias incident to axial and rotary motion of the hand wheel oppose motion of the lay.

ALEXANDER C. KRUKONIS.
